(57) **CLAIM**

The ornamental design for a bicycle frame element, as shown and described.

DESCRIPTION

Cross reference is made to copending U.S. design patent application Ser. No. 29/777,813 entitled “Bicycle Frame Element” by Nguyen, Quoc-Dat, which was filed on even date herewith; and U.S. design patent application Ser. No. 29/777,816 entitled “Bicycle Frame Element” by Nguyen, Quoc-Dat, which was filed on even date herewith.

FIG. 1 is a perspective view of a bicycle frame element showing my new design;

FIG. 2 is a left side elevational view of the bicycle frame element of FIG. 1;

FIG. 3 is a right side elevational view of the bicycle frame element of FIG. 1;

FIG. 4 is a rear side elevational view of the bicycle frame element of FIG. 1;

FIG. 5 is a front side elevational view of the bicycle frame element of FIG. 1;

FIG. 6 is a top side plan view of the bicycle frame element of FIG. 1; and,

FIG. 7 is a bottom side plan view of the bicycle frame element of FIG. 1.

The broken lines shown in the drawings illustrate portions of the bicycle frame element that form no part of the claimed design.
